UNITED STATES PATENT OFFICE

127,970

DESIGN FOR A MEASURING DEVICE

Benjamin C. Myers, Trenton, N. J.

Application April 17, 1941, Serial No. 100,467

Term of patent 14 years

To all whom it may concern:

Be it known that I, Benjamin C. Myers, a citizen of the United States of America, residing at Trenton, in the county of Mercer and State of New Jersey, have invented a new, original, and ornamental Design for Measuring Devices, of which the following is a specification, reference being had to the accompanying drawing, forming part thereof.

In the drawing:

Fig. 1 is a perspective view of a measuring device, showing my new design.

Fig. 2 is a side elevational view thereof;

Fig. 3 is an elevational view looking from the right of Fig. 2; and

Fig. 4 is a top plan view.

I claim:

The ornamental design for a measuring device, as shown,

BENJAMIN C. MYERS.
